UNITED STATES PATENT OFFICE.

GEORGE A. CONGDON, OF WEST SOMERVILLE, MASSACHUSETTS.

SINEW-EXTRACTOR.

941,759.

Specification of Letters Patent. Patented Nov. 30, 1909.

Application filed July 17, 1909. Serial No. 508,177.

To all whom it may concern:

Be it known that I, GEORGE A. CONGDON, of West Somerville, county of Middlesex, State of Massachusetts, have invented an 5 Improvement in Sinew-Extractors, of which the following is a specification.

This invention relates to sinew-extractors, and has for its object to construct a simple device adapted to be manually operated, 10 which may be supported on the wall, and when not in use may be arranged to occupy but little space.

Figure 1 is a front elevation of a sinew-extractor embodying this invention, the 15 parts being arranged in out-of-use position. Fig. 2 is a side view of the device shown in Fig. 1. Figs. 3 and 4 are details showing the parts in operative position, and Fig. 5 is a sectional detail to be referred to.

20 *a* represents a base which is adapted to be secured to the wall by screws or otherwise. To said base a foot-holder is secured by screws or otherwise, which, as here shown, consists of a bracket *b* comprising a base and 25 an arm projecting therefrom having a bifurcated end. Said arm projects forward and upward, and the space between the fingers of its forked end portion is made wide enough to receive the bony part of the leg, 30 as shown in Figs. 3 and 4; and furthermore, the adjacent faces or edges of said fingers, which form the opposite sides of the leg-receiving space, are beveled, as shown in Fig. 5, thereby providing for holding the leg 35 more securely by holding it obliquely, and also providing a sharp edge on the upper side of the lower finger of the forked end portion over which the leg may be easily broken.

40 *c* represents a claw, and *c'* a lever to which it is attached. Said lever is pivoted to the base *a*, at *c*², and, it will be observed, that said pivotal connection is arranged below and at one side of the foot-holder. The 45 claw *c* is arranged on the lever *c'* near its pivot and projects laterally from that side thereof adjacent the foot-holder, so that when the lever is raised on its pivot, from a

vertical to a horizontal position, or thereabout, see Fig. 3, said claw will engage the 50 leg below the foot-holder, and then as the lever is moved downward into the position shown in Fig. 4, the fleshy part of the leg will be drawn down while the bony part 55 will remain fixed in the foot-holder, resulting in the sinews being extracted from the fleshy part of the leg.

Ordinarily the device will be used but a few moments at a time, hence it is desirable to provide for compactly arranging the 60 parts when not in use and this is accomplished by permitting the lever to occupy a vertical position, close to or against the wall, as shown in Figs. 1 and 2, it being at such time suspended from its pivot. The 65 lever *c'* may be quite long without being cumbersome, and as the claw is arranged close to its pivot a powerful leverage is obtained.

Having thus described my invention, what 70 I claim as new and desire to secure by Letters Patent is:—

1. A sinew extractor consisting of a base, a forwardly extended foot-holder attached thereto having a forked end portion, a hand-lever pivoted at its upper end to said base, below and at one side of said foot-holder, which is movable on its pivot from a vertical to a horizontal position, and a claw 75 extended laterally from said lever at a point 80 intermediate its length on that side adjacent the foot-holder, which engages the leg below the foot-holder when the hand-lever is raised to a horizontal position and operates to separate the leg from the foot and extract 85 the sinew as the hand-lever is returned to vertical position, substantially as described.

2. A sinew extractor consisting of a base, a forwardly extended foot-holder attached thereto having a forked end portion, the adjacent faces of the fingers of said end portion being beveled, a hand-lever pivoted at its upper end to said base, below and at one side of said foot-holder, which is movable on its pivot from a vertical to a horizontal position, and a claw 90 extended laterally from

said lever at a point intermediate its length on that side adjacent the foot-holder which engages the leg below the foot-holder when the hand-lever is raised to a horizontal position and operates to separate the leg from the foot and extract the sinew as the hand-lever is returned to vertical position, substantially as described.

In testimony whereof, I have signed my name to this specification, in the presence of 10 two subscribing witnesses.

GEORGE. A. CONGDON.
